United States Patent Office.

HARRY H. EVARTS, OF CHICAGO, ILLINOIS.

Letters Patent No. 100,133, dated February 22, 1870; antedated February 14, 1870.

IMPROVED BEDSTEAD.

The Schedule referred to in these Letters Patent and making part of the same.

To all whom it may concern:

Be it known that I, HARRY H. EVARTS, of Chicago, in the county of Cook, and State of Illinois, have invented a new and useful "Improvement in Bedsteads;" and I do hereby declare the following to be a full, clear, and exact description of the same, reference being had to the accompanying drawings and the letters and figures marked thereon which form a part of this specification, and in which—

Figure 1 represents a longitudinal vertical sectional view of my improved bedstead;

Figure 2, a transverse sectional view of the same; and

Figure 3, a top view of the corner piece A, detached.

The nature of my invention consists in the corner pieces A that are secured to the inner corners of the bedstead-frame, and provided with a flange, B, to which the bedstead-leg is secured, as hereafter more fully described.

To enable those skilled in the art to understand how to manufacture and use my invention, I will proceed to describe the same with particularity.

The same letters of reference refer to the corresponding parts in the different figures.

This improvement is more particularly adapted to be used in the manufacture of the best kind of bedsteads.

The joints at the corners are made firm and secure by the pieces A which are screwed to the side and end pieces, holding them firmly together.

Any ornamental pieces like the pieces B may be

fastened in place by a screw passing through the piece A.

There is a flange, C, on the bottom of the corner piece A, and the leg D of the bedstead is firmly secured to that flange by means of screws, the flange also forming a support for the bed-bottom.

There is no danger of breaking the flange C by any weight resting upon it, because it rests directly on top of the leg D of the bedstead.

The bedstead may be made in any of the usual styles, so far as the side and end pieces are concerned, and the head-board and foot-board may be of any size or design, it being simply the object of the corner piece A to be so formed that it will fit into the corner, and be sufficiently large so that all the parts of the bedstead can be fastened to it by means of screws.

The flange C resting on top of the leg, and being firmly screwed thereto, the entire bedstead is made solid and firm, with no danger of falling apart.

Having thus fully described the construction and operation of my improved bedstead,

What I claim, and desire to secure by Letters Patent, is—

The corner piece A, provided with the flange C, in combination with the legs, ends, and side pieces of a bedstead, when all are constructed and arranged substantially as described and shown.

HARRY H. EVARTS.
